FIG.9

FIG.7

FIG.8

FIG. 1 is a perspective view of a plumb bob showing our new design with the suspension means disposed in one pivoted position thereof;

FIG. 2 is a front elevational view thereof;

FIG. 3 is a side elevational view thereof, the opposite side being a mirror image thereof;

FIG. 4 is a rear elevational view thereof;

FIG. 5 is an elevational view of the lower end thereof as seen in FIG. 2;

FIG. 6 is an elevational view of the upper end thereof as seen in FIG. 2;

FIG. 7 is a view of the plumb bob with the suspension means pivoted ninety degrees from the position shown in FIGS. 1–6 so that the body portion thereof may be suspended horizontally, the illustration of FIG. 7 thus being a top view in this position;

FIG. 8 is a side elevational view of the plumb bob with the suspension means in the position of FIG. 7, the opposite side view being identical; and

FIG. 9 is a front elevational view of the plumb bob in the pivoted position of FIG. 7, the rear elevational view being identical.

We claim:

The ornamental design for a plumb bob, as shown and described.
